Application June 23, 1948, Serial No. 147,138

Term of patent 14 years

(Cl. D85—2)

To all whom it may concern:

Be it known that we, Edward San Giovanni (1) and Ernest Sohn (2), both citizens of the United States of America, residing (1) at Ridgefield, in the county of Fairfield and State of Connecticut, (2) at New York, county of New York, and State of New York, have invented a new, original, and ornamental Design for a Combined Cigarette and Lighter Holder, of which the following is a specification, reference being had to the accompanying drawing, forming part thereof.

Fig. 1 is a front view of a combined cigarette and lighter holder, showing our new design, and

Fig. 2 is a top plan view thereof, taken along the line 2—2 of Fig. 1.

We claim:

The ornamental design for a combined cigarette and lighter holder, as shown and described.

EDWARD SAN GIOVANNI.
ERNEST SOHN.
